METAL SPRAY APPARATUS

William H. Stevens, San Francisco, Calif.

Application July 6, 1937, Serial No. 152,094

6 Claims. (Cl. 91—12.2)

This invention relates to a metal spray apparatus, and especially to a single control lever or hand grip whereby the several valves regulating the flow of air and gas to the turbine and burner nozzle may be opened and closed in proper sequence, and whereby the wire feeding rolls may be simultaneously actuated either to release or to grip the metal wire as the gas valves are closed.

10 In the operation of metal spray guns, the acetylene and oxygen gases delivered to the burner nozzle are usually regulated by individual valves, and so is the air which is employed for atomizing and projecting the molten metal and

15 for operating the turbine whereby the wire feeding wheels are driven; and in addition thereto the wire feeding wheels must be adjusted to release or grip the wire being fed thereby. All these valves and adjustments require continuous

20 attention and care, if uniform results are to be insured. Once they are adjusted, the operator does not like to close them off when he momentarily stops for one reason or another, as too much time is consumed in opening and read-

25 justing the valves, hence, excessive amounts of gas and air are consumed, and besides that, the gun is subjected to unnecessary use and wear without producing any results.

The object of the present invention is to generally improve and simplify the construction and operation of apparatus of the character described; to provide a control which permits almost instantaneous opening and closing of all the valves in proper sequence, and simultaneous actuating

5 of the wire feeding wheels; further, to provide a control which permits individual adjustment of the several valves; to insure the proper proportions of gases, atomizing air, etc., for metal wire of varying diameter and melting point; and

10 which also permits adjustment of the wire feeding wheels for metal wire of varying diameter or gauge.

The apparatus is shown by way of illustration in the accompanying drawings, in which

Fig. 1 is a central, vertical, longitudinal section of the metal spray apparatus;

Fig. 2 is a side elevation, partially in section, of a mixing tube whereby the oxygen and acetylene gas are thoroughly mixed before being admitted to the burner nozzle;

Fig. 3 is a cross section taken on line III—III of Fig. 1;

Fig. 4 is a cross section taken on line IV—IV of Fig. 2;

Fig. 5 is a bottom view of Fig. 2;

Fig. 6 is a plan view of the spray apparatus, said view being partially broken away and being partially in section;

Fig. 7 is a horizontal section taken on line VII—VII of Fig. 1;

Fig. 8 is a rear view of the spray apparatus, said view being partially in section to show the turbine wheel and the chamber in which it is mounted; and

Fig. 9 is a perspective view of one of the rocker arms supporting one of the shafts whereby one of the wire feeding wheels is supported and driven.

Referring to the drawings in detail, and particularly to Fig. 1, A indicates a base plate on the under side of which is formed a handle 2 in the form of a pistol grip, and on the upper surface of which is formed a standard 3. Secured to the base plate by screws 5 or similar means (see Figs. 1 and 8) is a housing B, and forming a part 20 thereof is a head member C to which is secured a nozzle generally indicated at D. Formed within the housing B is a main chamber E which encloses a multi-speed gear transmission F and a worm gear reduction drive G, said reduction gears 25 being driven by a turbine wheel H mounted in a chamber formed in the rear end of the housing, said chamber having a discharge passage 6 to permit free escape of the air by which the turbine wheel is driven, as will hereinafter be described.

The multi-speed gear transmission F terminates in a pair of drive shafts 7—7 (see Fig. 7) which transmit power through chain drives such as shown at 8—8 to a pair of shafts 9—9, which 35 will hereinafter be referred to as the wire feeding wheel driving shafts, as each of them supports and drives a wire feeding wheel such as shown at 10. These wheels are movable to and away from each other, to engage or release a 40 wire such as shown at 11, first of all to either grip or release the wire, and secondly to permit wire of different diameter or gauge to be used. It is accordingly essential that the shafts 9—9 be mounted in bearings which are adjustable to and away from each other, as the shafts must obviously move in unison with the wire feeding wheels supported and driven thereby. The mounting for each of the shafts 9 is identical with that for the other, and a description of 45 one should accordingly suffice.

Referring to Fig. 9, one of the shafts 9 is shown. This shaft is journaled in bearing lugs 12—12 forming an integral part of, or secured to, a vertically disposed shaft 13. The upper

end of the shaft 9 is square, to receive and support a wire feeding wheel 10 and to form a driving connection between the shaft and said wheel. A sprocket gear is secured to the shaft 9 between the bearings 12-12, and this is driven from shaft 7 by means of the chain drive 8. The upper end of the shaft 13 is provided with a rocker arm 14 and the outer end thereof terminates in a cone-shaped beveled face 15, the function of which will hereinafter be described. The standard 3 formed in the base member 8 has two recesses formed in its upper end to receive the shaft members 13, and when the shafts together with the bearing lugs, rocker arms, etc., are placed therein, they will assume the position shown in Fig. 7.

Extending vertically through the standard 3 is a rod 16, the upper end of which is provided with a cone-shaped cam 17; the lower end of the rod projects through a control lever 18 pivoted to the handle 2 as at 19. The lower end of the rod is threaded, and an adjustable connection is formed between the lever 18 and the rod, by adjusting nuts 20. If a wire 11 of a certain diameter is to be gripped and fed forwardly through the nozzle D by means of the wire feeding wheels 10, it is only necessary for the operator to grasp the control lever 18 and pull it towards the handle 2, and in so doing, a downward pull is exerted on the rod 16. The cone-shaped cam 17 formed in the upper end thereof will engage the complementary faces 15 formed in the outer ends of the rocker arms 14. They will accordingly be spread apart, causing the shafts 13 to turn about their longitudinal axes and to swing the bearing lugs 12 together with the shafts 9 and the wire feeding wheels 10 towards each other, thus gripping the wire and feeding it forwardly through the nozzle, if the turbine is in operation, as power will be transmitted from the turbine through the reduction gear drive and the transmission F to the shafts 7-7, and from these to the shafts 9-9 by means of the chain drives 8-8, the chain drives being similarly flexible to permit arcuate movement of the shafts 9-9 about their pivotal points or shaft 13-13, as previously described.

In actual practice, a series of flexible hose are connected with the housing B at the points indicated at 25, 26 and 27. The hose 27 delivers air under comparatively high pressure, the hose 26, acetylene, and the hose 25, oxygen gas. The hose 27 is connected with two passages, one indicated at 28 and one at 29. The passage 28 is a by-pass passage and connects with a nozzle or orifice 30 which delivers air under pressure to the vanes of the turbine to drive the same. A manually adjustable needle valve 31 or similar means is used in connection with the orifice or nozzle to regulate the flow of air. The main passage 29 extends upwardly through the housing B into the head member C, and in this head is formed a connected extension passage 32 which in turn connects with an annular chamber 33 formed in the nozzle D. This chamber delivers the air to the numerous discharge orifices shown at 34, said orifices serving the function of directing the air against the melting portion of the wire to atomize and project the same, and to control the fine spread of the molten metal. A valve 35 controls the flow of air through the passage 29, or in other words, the flow of air to the atomizing nozzle D. This valve is normally held against its seat in closed position by means of the spring 36. It is provided with a stem 37 which pro-

jects through a stuffing box 38 and the lower end of the valve is provided with adjusting nuts 39 which are engaged by a fork 40 of the control lever 18.

The acetylene gas is admitted through the connection 26 and its flow is controlled by a valve 41 identical in construction to the valve 35. The valve stem connected with the valve 41 is also provided with adjusting nuts as shown at 42, and it extends through the fork 43 forming a part of the control lever 18. The oxygen enters through the connection 25. Its flow is also controlled by a valve such as shown at 44. This valve is similar in construction to the valves 35 and 41, and its stem is provided with adjusting nuts 45 which are engaged by a fork 46 of the control lever 18. The oxygen and acetylene gases are combined and thoroughly mixed before being delivered to the burner nozzle, and this is accomplished in the present instance by a mixing tube generally indicated at 47 (see Figs. 2, 3, 4 and 5); the lower end of the tube forms a valve seat for the valve 44; the center portion is reduced in diameter to form an annular recess or chamber 48 into which the acetylene gas is introduced through a by-pass passage 49; and the upper end of the tube is provided with a head 50 in the outer surface of which are formed angularly formed slots 51. The oxygen admitted by the valve 44 passes upwardly through a central passage 52 formed in the tube. At the upper end of this passage are lateral passages 53 which communicate with the slots 51, and as the other gas is also flowing through these slots, the two gases meet and mix, and they are further mixed due to the swirling movement imparted to the gases when they discharge into a chamber 54 formed above the tube. From there the mixed gases pass through a duct or passage 55 and 56. The passage 56 enters the head C and then a passage 57 (see Fig. 6) which delivers the mixed gases to an annular chamber 58. From there the gases flow forwardly through an annular chamber 59, and finally discharge through an orificed plug 60 to a point forwardly of the nozzle D, where combustion takes place. The wire 11 is fed through this zone of combustion, and the temperature maintained is sufficient to fuse and melt the metal and permit atomization and projection thereof by the compressed air delivered from the annular chamber 33.

The spray apparatus here shown is exceedingly simple to handle. The valves controlling the flow of air to the atomizing nozzle, and the flow of oxygen and acetylene gas, are all independently adjustable, by means of the nuts indicated at 39, 42 and 45, and they will be adjusted until the proper proportion of gas and air is obtained, and when so adjusted the nuts 39, 42 and 45 are locked and permanently set. Thereafter when the operator desires to use the gun he merely applies pressure to the lower end of the control lever 18, and as he does so he will open the valves 35, 41 and 44 in consecutive order, as the forks on the upper ends thereof will successively engage the adjusting nuts 39, 42 and 45. Similarly, when he desires to close these valves, he merely releases pressure on the lever 18, and the valves will then all close in successive order, but their adjustment will not be disturbed. When the valves are opened the rod 16 is simultaneously actuated, and the wire feeding wheels are thus automatically brought together to drive and feed the wire through the zone of combustion maintained at the forward end of the nozzle 75

zle, these wheels similarly releasing their grip on the wire when the control lever is released and the valves closed. The speed of the turbine may be regulated at any time by the manually controlled needle valve 31. No other controls are required. Varying speeds may be transmitted to the wire feeding rolls depending upon the diameter of the wire being fed, or the melting point of the same, these speeds being controlled by the multi-speed transmission F. This transmission, together with the gear reduction drive and other parts of the mechanism, forms the subject matter of two co-pending applications, both entitled Metal spray apparatus, filed of even date. For this reason, a detailed description thereof is thought unnecessary.

While the adjusting mechanism between the individual valves and the lever 18, and between the rod 16 and the lever 18 is more or less specifically described and illustrated, I wish it understood that this adjustment, together with other features of the invention, may be changed within the scope of the appended claims, and that the materials and finish of the several parts employed may be such as the manufacturer may decide or varying conditions or uses demand.

Having thus described and illustrated my invention, what I claim and desire to secure by Letters Patent is the following:

1. In an apparatus of the character described, a burner nozzle, wire feeding wheels to feed a metal wire through the nozzle, means for delivering a combustible gas and atomizing air to the nozzle, valves for regulating the flow of air and gas to the nozzle, and a common control for opening or closing the valves and for simultaneously moving the wire feeding wheels to or away from the wire to grip and feed the wire or release the same.

2. In an apparatus of the character described, a burner nozzle, wire feeding wheels to feed a metal wire through the nozzle, means for delivering a combustible gas and atomizing air to the nozzle, valves for regulating the flow of air and gas to the nozzle, a common control for opening or closing the valves and for simultaneously moving the wire feeding wheels to or away from the wire to grip and feed the wire or release the same, and means for adjusting the gripping position of the wire feeding wheels with relation to the common control.

3. In an apparatus of the character described, a burner nozzle, wire feeding wheels to feed a metal wire through the nozzle, means for deliv-

ering a combustible gas and atomizing air to the nozzle, a plurality of valves for regulating the flow of air and gas to the nozzle, a common control for opening or closing the valves and for simultaneously moving the wire feeding wheels to or away from the wire to grip and feed the wire or release the same, and means for adjusting each valve to regulate the flow of gas and air with relation to the common control.

4. In an apparatus of the character described, a burner nozzle, wire feeding wheels to feed a metal wire through the nozzle, means for delivering a combustible gas and atomizing air to the nozzle, a plurality of valves for regulating the flow of air and gas to the nozzle, a common control for opening or closing the valves and for simultaneously moving the wire feeding wheels to or away from the wire to grip and feed the wire or release the same, means for adjusting the gripping position of the wire feeding wheels, and means for adjusting the valves with relation to the common control to regulate the flow of gas and air.

5. In an apparatus of the character described, a burner nozzle, an air atomizing nozzle surrounding the same, wire feeding wheels to feed a metal wire through the nozzle, means for delivering a mixture of oxygen and a combustible gas to the burner nozzle, a separate valve for each of said gases to regulate the flow of the same, a valve to regulate the flow of atomizing air to the air nozzle, and a common control for opening or closing the valves and for simultaneously moving the wire feeding wheels to or away from the wire to grip and feed the wire or release the same.

6. In an apparatus of the character described, a burner nozzle, an air atomizing nozzle surrounding the same, wire feeding wheels to feed a metal wire through the nozzle, means for delivering a mixture of oxygen and a combustible gas to the burner nozzle, a valve for each of said gases to regulate the flow of the same, a valve to regulate the flow of atomizing air to the air nozzle, a common control for opening or closing the valves and for simultaneously moving the wire feeding wheels to or away from the wire to grip and feed the wire or release the same, means for adjusting the gripping position of the wire feeding wheels with relation to the common control, and means for adjusting the valves with relation to the common control to regulate the flow of gas and air.

WILLIAM H. STEVENS.
